UNITED STATES PATENT OFFICE

160,727

COMBINATION TELEVISION, RADIO,
PHONOGRAPH CABINET

Joseph McRae, New York, N. Y.

Application May 24, 1950, Serial No. 10,145

Term of patent 7 years

(CL. D56—4)

To all whom it may concern:

Be it known that I, Joseph McRae, a citizen of the United States, residing at New York, in the county of Kings and State of New York, have invented a new, original, and ornamental Design for a Combination Television, Radio, Phonograph Cabinet, of which the following is a specification, reference being had to the accompanying drawing, forming part thereof.

In the drawing

Fig. 1 is a front perspective view of a combination television, radio, phonograph cabinet, with the doors closed, showing my new design;

Fig. 2 is a front perspective view thereof, with the doors open.

The rear of the cabinet is plain.

I claim:

The ornamental design for a combination television, radio, phonograph cabinet, as shown and described.

JOSEPH McRAE.
